(57) **CLAIM**

The ornamental design for a trach tie, as shown and described.

DESCRIPTION

FIG. 1 is a top left perspective view of a trach tie showing my new design;

FIG. 2 is a top right perspective view thereof;

FIG. 3 is a bottom right perspective view thereof;

FIG. 4 is a front view thereof;

FIG. 5 is a back view thereof;

FIG. 6 is a top view thereof;

FIG. 7 is a bottom view thereof;

FIG. 8 is a left view thereof; and,

FIG. 9 is a right view thereof.

The trach tie is shown with a symbolic break in its length. The appearance of any portion of the article between the break lines forms no part of the claimed design. It is being understood that the present invention has a uniform shape and appearance throughout the length of the present invention.

The broken lines showing tapered ends are included for the purpose of illustrating environmental structure and form no part of the claimed design.
